DENTIST'S MODEL

Filed Nov. 20, 1930

Fig. 1.

Fig. 2.

UNITED STATES PATENT OFFICE

WALTER KÖHLER, OF MUNICH, GERMANY

DENTIST'S MODEL

Application filed November 20, 1930, Serial No. 496,919, and in Germany September 23, 1930.

My invention relates to dentists' models, and more particularly to models having an upper and a lower jaw arranged for the demonstration of mastication movements and of abnormal positions of the human lower jaw. The model may also be used in dentistry as a so-called articulator for making artificial teeth.

It is an object of my invention to provide a model in which the movable jaw may be fixed on a foundation plate in any desired position. To this end I mount the movable jaw to slide on the foundation plate in all directions and I provide means for fixing it in any desired position. Preferably I also provide means for varying the angular position of the movable jaw with respect to the foundation plate.

In the drawing affixed to this specification and forming part thereof a model embodying my invention is illustrated diagrammatically by way of example.

In the drawing

Fig. 1 is a central longitudinal section, Fig. 2 is a section on the line II—II in Fig. 1,

Fig. 3 is a plan view of the foundation plate, with the jaws removed, and

Figs. 4 and 5 are details.

Referring to the drawing, 1 is the foundation plate, 2 and 3 are uprights extending upwardly from the plate, 4 is a pin supported in the upper ends of the two uprights, and 5 is the upper jaw which is mounted to rock on the pin 4 with its forked ends 6. 7 is a slide bar extending between the uprights 2 and 3 in the manner of a stay and in parallel relation to the pin 4. 8 is a block which is mounted to slide on the pin. 9 is a set screw in the block for fixing it on the pin. 10 is a flat cheek on the inner end of the block 8 (Fig. 5) and 11 is a corresponding face on one of the ends 6 of the upper jaw 5. The block 8 is held against rotation on the pin 4 by the bar 7, and when it is moved into the position shown in Fig. 5, its cheek 10 locks the upper jaw 5 in the position illustrated in Fig. 1.

12 is the lower jaw which is also forked at its rear end, and with its forked ends 13

and 14 engages the ends of a shaft 16 which projects from a bracket 15. The forked ends 13, 14 are secured on the ends of the shaft 16 by means of pins 17 and 18, or other suitable means, so that the shaft 16 rotates in the bracket when the lower jaw 12 is rocked. The bracket 15 is equipped with a handle 19 which projects from the model at the left. The bracket surrounds a pin 20 on the foundation plate 1. 21 is a plate with rounded ends which is placed with its opening 22 on the pin 20 so as to surround it with considerable clearance, while the plate is in turn surrounded with some clearance by the bracket 15. 23 is a rectangular washer at the base of pin 20, and 24 is an annular projection on the bottom face of the plate 21 by which it is supported on the washer 23. 25 is a V-notch or seat near the rounded inner end of the plate 21, and 26 is a corresponding notch in a plate 27 which resembles the plate 21, with a corresponding opening 28 for the reception of the pin 20. 29 is a pin which is inserted in registering bores of the plates 21 and 27. 30 is a washer which is placed on the upper plate 27, and 31 is a nut on the threaded upper end of the pin 20 which bears on the washer 30.

When the nut 31 is set, the plates 21 and 28 are held down on the rectangular washer 23 of the foundation plate 1 in any desired position with respect to the pin 20. At the same time shaft 16 is clamped in the notches or bearings 25 and 26 of the plates. The plates 21 and 27 thus constitute a frame which is surrounded by the bracket 15 and connected thereto by the shaft 16 of the lower jaw 12.

When the nut 31 is partly unscrewed, the frame 21, 27 may be displaced longitudinally and transversely. As mentioned, the opening 22 and the opening 28 which registers with the opening 22, surround the pin 20 with considerable clearance and a corresponding freedom of movement in all directions is permitted to the frame 21, 27 and also to the bracket 15 which is connected to the frame by the pin 16. While the frame and the bracket are displaced the free end of the movable jaw 12 slides on the foundation

plate, adjustment being facilitated by the handle 19. By setting the nut 31 the frame 21, 27, and consequently also the jaw 12 are fixed in any given position.

5 32 is a slide which is fitted in a notch 33 extending lengthwise of the foundation plate 1, 34 is a handle near its outer end and 35 is a set screw for fixing same in any given position, 36 being a slot in the slide for the reception of the screw 35. The slide forms part of the foundation plate 1 and normally supports the free end of the lower jaw 12 so that the jaw is only displaced in parallel to the foundation plate by the handle 19. 37 is a 10 step or shoulder near the front end of the slide 32.

When the slide is retracted so that the step 37 is moved beyond the outer end of the lower jaw 12, the jaw is free to rock about the axis 20 of its shaft 16 so that its angular position with respect to the foundation plate 1 may be varied. Obviously the nut 31 must be partly unscrewed to permit the shaft 16 to rock in the V-notches 25 and 26 of the frame 21,

25 27. By setting the nut 31 the lower jaw 12 is held in the position imparted to it by the handle 19, and at the angle through which it has been rocked about the shaft 16.

Means for exactly fixing the lower jaw in 30 its normal position may be combined with the slide 32, as will now be described. 38 is a pin near the front end of the slide 32, which is adapted to enter a notch 39, and 40 and 41 are two pins near the rear end of the 35 slide which are adapted to enter notches 42 and 43, respectively, in the inner face of the bracket 15, when the slide 32 is pushed home. Corresponding notches 44 and 45 are provided in the inner edge of the rectangular 40 washer 23.

The upper and lower jaws have been illustrated as being equipped with teeth. If the teeth are omitted and the jaws are suitably modified, the model may be used as a so-called articulator, as described in my co-pending application for patent of the United States, Serial No. 369,327, filed June 8, 1929, in which I have described jaws in combination with exchangeable gum models and exchangeable teeth adapted to be inserted in the models.

I wish it to be understood that I do not desire to be limited to the exact details of construction shown and described, for obvious modifications will occur to a person skilled in the art.

I claim:

1. A dentist's model comprising a foundation plate, a pin on said foundation plate, a 50 frame surrounding said pin with an opening which is larger than said pin, a jaw attached to said frame at one end and supported on said foundation plate at the other end, and means on said pin for fixing said frame on said plate in any desired position.

2. A dentist's model comprising a foundation plate, a pin on said foundation plate, a frame surrounding said pin with an opening which is larger than said pin, a jaw pivoted to said frame at one end and supported on said foundation plate at the other end, and means on said pin for fixing said frame on said plate in any desired position. 70

3. A dentist's model comprising a foundation plate, a pin on said foundation plate, a frame surrounding said pin with an opening which is larger than said pin, said frame including two members each having a depression, a shaft inserted in said depressions, said depressions matching and together forming a single seat for said shaft, a jaw secured to said shaft at one end and supported on said foundation plate at the other end, and means on said pin for clamping said shaft in said depressions and for fixing said frame on said plate in any desired position. 75

4. A dentist's model comprising a foundation plate, a pin on said foundation plate, a frame surrounding said pin with an opening which is larger than said pin, a bracket spaced apart from and connected to said frame, a handle on said bracket, a shaft mounted to rotate in said bracket, a jaw secured to said shaft at one end and supported on said foundation plate at the other end, means on said frame for clamping said shaft, and means on said pin for setting said clamping means and for fixing said frame on said plate in any desired position. 80

5. A dentist's model comprising a foundation plate, a pin on said foundation plate, a frame surrounding said pin and adapted to be displaced with respect thereto in all directions, a jaw pivoted to said frame at one end, a slide on said foundation plate adapted to support the other end of said jaw, means on said slide for engaging said jaw and said frame so as to hold said jaw in a definite position, and means for fixing said slide on said foundation plate. 100

6. A dentist's model comprising a foundation plate, a jaw pivotally mounted on said foundation plate at one end, a slide on said foundation plate adapted to support the other end of said jaw, means on said slide for engaging said jaw so as to hold said jaw in a definite position, and means for fixing said slide on said foundation plate. 105

7. A dentist's model comprising a foundation plate, a pin on said foundation plate, a frame embracing said pin and being mounted to slide on said foundation plate and adapted to be displaced thereon in all directions within the limits set by said pin, and means for fixing said frame on said foundation plate in any position into which it has been displaced. 110

8. A dentist's model comprising a foundation plate, a pin on said foundation plate, a frame embracing said pin and surrounding 115

5 said pin with a clearance and mounted to slide on said foundation plate and adapted to be displaced thereon in all directions within the limits set by said pin, and means for fixing said frame on said foundation plate in any position into which it has been displaced.

10 9. A dentist's model comprising a foundation plate, a pin on said foundation plate, a frame embracing said pin and being mounted to slide on said foundation plate and adapted to be displaced thereon in all directions within the limits set by said pin, and means on said fixture for fixing said frame on said foundation plate in any position into which it has been displaced.

15 10. A dentist's model comprising a foundation plate, a pin on said foundation plate, a jaw embracing said pin and being mounted to slide on said foundation plate and adapted to be displaced thereon in all directions within the limit set by said pin, means for varying the angular position of said jaw with respect to said foundation plate, and means for fixing said jaw on said plate in any position into which it has been displaced.

20 11. A dentist's model comprising a foundation plate, a pin on said foundation plate, a frame embracing said pin and being mounted to slide on said foundation plate and adapted to be displaced thereon in all directions within the limits set by said pin, means for fixing said frame on said foundation plate in any position into which it has been displaced, and a jaw pivoted to said frame.

25 12. A dentist's model comprising a foundation plate, a pin on said foundation plate, a frame embracing said pin and being mounted to slide on said foundation plate and adapted to be displaced thereon in all directions within the limits set by said pin, means for fixing said frame on said foundation plate in any position into which it has been displaced, and a jaw pivoted to said frame at one end, with its free end bearing on said plate.

30 13. A dentist's model comprising a foundation plate, a pin on said foundation plate, a frame made up of two parts surrounding said pin with an opening which is larger than said pin, a shaft inserted between the two parts of said divided frame and extending at right angles to said pin, a jaw secured to

35 said shaft at one end, means on said pin for clamping down said divided frame on said foundation plate, at the same time clamping said shaft between the two parts of the divided frame, and a slide on said foundation plate adapted to support the other end of said jaw.

40 14. A dentist's model comprising a foundation plate, a pin on said foundation plate, a frame made up of two parts surrounding said pin with an opening which is larger than said pin, a shaft inserted between the two parts of said divided frame and extending at right angles to said pin, a stepped jaw secured to said shaft at one end, means on said pin for clamping down said divided frame on said foundation plate, at the same time clamping said shaft between the two parts of the divided frame, and a slide on said foundation plate adapted to support the other end of said stepped jaw.

45 15. A dentist's model comprising a foundation plate, an upper jaw pivotally mounted on said foundation plate, means for fixing said upper jaw in a given angular position with respect to said foundation plate, a pin on said foundation plate, a lower jaw embracing said pin and mounted to slide on said foundation plate in all directions within the limits set by said pin, and means for fixing said lower jaw on said foundation plate in any position into which it has been moved.

50 16. A dentist's model comprising a foundation plate, a pivot supported above said foundation plate, an upper jaw mounted to rock about said pivot, a block mounted to slide on said pivot, means for holding said block against rotation, a cheek on said block and a corresponding cheek on said upper jaw, said cheek being so designed as to hold said upper jaw against rotation on said pin when engaged, a pin on said foundation plate, a lower jaw embracing said pin and mounted to slide on said foundation plate in all directions within the limits set by said pin, and means for fixing said lower jaw on said foundation plate in any position into which it has been moved.

55 In testimony whereof I affix my signature.
WALTER KÖHLER.
